INVENTOR,

BY Richard Oliver,

ATTORNEY.

UNITED STATES PATENT OFFICE.

EDWARD G. SPINDLER, OF ST. LOUIS, MISSOURI.

GAGE.

1,321,567.

Specification of Letters Patent. Patented Nov. 11, 1919.

Application filed October 21, 1916. Serial No. 126,957.

To all whom it may concern:

Be it known that I, EDWARD G. SPINDLER, a citizen of the United States, residing at St. Louis, and State of Missouri, have invented certain new and useful Improvements in Gages, of which the following is a specification.

This invention relates to certain new and useful improvements in a gage and has for its primary object the provision of a device of this character which will be of extremely simple construction, inexpensive and highly efficient in use.

Another object of the invention resides in the provision of a gage of the above-stated character which may be readily adjusted to determine either interior or exterior dimensions by the adjustment of a single movable member upon the scale, said movable member being adjusted toward or away from a stationary coöperating member rigidly secured to the scale bar.

A further object of the invention resides in the provision of a novel form of scale bar and coöperating members mounted upon the same, as well as a simple form of securing means to hold the measuring jaws in proper position.

With these general objects in view and others that will appear as the nature of the invention is better understood, the same consists in the novel combination and arrangement of parts hereinafter more fully described, illustrated in the accompanying drawings, and pointed out in the appended claim.

In the drawings forming a part of this application and in which like-designating characters refer to corresponding parts throughout the several views:

Figure 1 is an elevation of the complete device,

Fig. 2 is a detail elevation of the scale bar showing the rear face of the same,

Fig. 3 is a sectional view taken on line 3—3 of Fig. 1,

Fig. 4 is a fragmentary plan looking at the rear edge of the gage, and

Fig. 5 is a detail section through one of the securing members.

Referring more particularly to the drawings, 1 designates the outer measuring jaw which is provided with a flat inner face and an extension 3 at its forward side. The outer measuring jaw 1 is adapted for coöperation with the inner adjustable measuring

jaw 4 which also has a flat inner face 5 parallel with the face 2 of the jaw 1, and an extension 6 projecting from its forward side, parallel with the extension 3 of said jaw 1. The jaw 4 and the inner faces 2 and 5 may coöperate in the work of obtaining exterior dimensions, while the extensions 3 and 6 coöperate in the work of obtaining interior dimensions, as will be later clearly understood.

The jaws 1 and 4 are mounted upon the scale bar 7 which has a central longitudinal groove 8 in its front face and extended practically the entire length of the same.

The outer jaw 1 is preferably secured upon the forward end of the scale bar 7 and held in position by means of the securing member 9 which is engaged in a groove 10 of the member 1 and has one end 11 bent at a right angle and engaged in the groove 8 of the bar 7, the opposite end of said securing member 9 being threaded as shown at 12 to receive the cap 13, which has a spring 14 positioned therein and bearing against the end of said securing member 9 to frictionally retain the head 13 in proper position. The portion of the member 9 resting in the groove 10 of the outer jaw 1 and engaged with the outer face of the lower portion of the scale bar 7, is reduced in thickness, thereby providing the shoulder 15 at the connection of said portion with the long portion of said member 9, the shoulder 15 resting against the edge of the scale bar 7, as will be readily seen by referring to Fig. 3 of the drawings. The outer head 1 is also provided with a transverse recess or opening 16 within which the head 13 of the securing member 9 is positioned, whereby said cap 13 may be readily adjusted upon the member 9.

The inner adjustable head 4 is also provided with an opening 16 to accommodate the head 13 of a second securing member 9 which is employed for securing the inner jaw 4 in adjusted position upon the scale bar 7.

In assembling my improved gage each of the securing members 9 is inserted in the groove or opening 10 in the jaws 1 and 4 respectively. The scale bar 7 is now inserted through the open ended slot 10 in the jaw 4 while the jaw 1 is engaged upon one extremity of the scale bar. The end 11 of each of the securing members 9 is accommodated in the groove 8 as clearly

shown in Fig. 3. The nuts 13 are now threaded on the threads of these securing members 9 until they bind against the jaws 1 and 4 respectively, and this will prevent the jaws moving on the bar 7.

The body of the inner adjustable jaw 4 is provided with a sight opening 17 which is of such size and shape as to disclose portions of the scales 18 and 19, upon the front face 10 of the scale bar 7. In the drawing only one of these openings 17 is shown but it is to be understood that a second opening is to be formed in the opposite side of the jaw 4. The scale 18 is located upon the lower portion of the front face of the scale bar 7 and is especially adapted for use in obtaining the exterior measurements of a shaft or the like up to and including a six inch shaft. The scale 19 is designed for indicating the size of standard bolts, and it will be understood that each opening 17 has a depressed portion or flange 22 formed therearound and provided with indicating marks 23 upon its outer face which will serve to indicate 25 upon the scales the size of the article being measured. The scale 21 on the upper portion of the opposite side of the scale bar 7 may be employed when determining the size of a hole to be drilled for a pipe thread. 30 The scale 20 on the lower portion of this side of the scale bar 7 will also be found useful in obtaining various measurements of different articles.

From the foregoing, it will be evident 35 that the inner jaw 4 may be readily adjusted upon the scale bar 7 and for the purpose of moving the jaw 4 upon the scale bar 7, I have provided a recess or depression 24 which is roughened in the upper 40 edge of the body of the jaw 4 to receive the operator's thumb, while notches 25 are formed at the lower outer corner of the body of said jaw 4 to accommodate the operator's finger when either drawing the jaw 4 away 45 from the jaw 1, or forcing said jaw 4 toward

the jaw 1. A spacing strip 24' is positioned between the separated extended portions of the jaw 4, and the portion of said strip 24' in the recess or depression 24, is also roughened, as shown in Fig. 4. The complete device is of simple construction and operation and may be readily manipulated with one hand. 50

It will be noted that the slot or recess provided in the body of the inner jaw 4 to receive the scale bar 7 has an open end at one edge of said jaw to permit removal of the scale bar. A removable block 24' secured between the side walls of the slot adjacent the open edge thereof, normally retains the scale bar in position, but this block can be readily removed when desired. 55

While the form of the invention herein shown and described is what is believed to be the preferred embodiment thereof, it is nevertheless to be understood that minor changes may be made without departing 65 from the spirit and scope of the invention as claimed.

What I claim as new is—

A gage comprising a scale bar, jaws slideable thereon, one of said jaws having a slot extending longitudinally through the body portion thereof to receive said scale bar, said slot having an open end at the upper 70 edge of said body and including side and bottom walls closely embracing said scale bar, a removable block closing the upper portion of said slot to retain the scale bar 75 therein, and means for drawing the scale bar into tight frictional engagement with the bottom wall of said slot to lock the jaws in adjusted position.

In testimony whereof I affix my signature in presence of two witnesses.

EDWARD G. SPINDLER.
